(57) **CLAIM**

The ornamental design for display-coupled financial transaction card, as shown and described.

DESCRIPTION

FIG. 1 is a perspective view of our financial transaction card coupled to a display;

FIG. 2 is a front view of the display-coupled financial transaction card shown in FIG. 1;

FIG. 3 is a back view of the display-coupled financial transaction card show in FIG. 1, in which the display includes an opening through which a portion of the financial transaction card is visible;

FIG. 4 is a perspective view of our financial transaction card coupled to another embodiment of a display that differs from the display of FIG. 1 in that the certain lettering is omitted from the display;

FIG. 5 is a front view of the display-coupled financial transaction card shown in FIG. 4; and,

FIG. 6 is a back view of the display-coupled financial transaction card show in FIG. 4.

The dashed lines in the figures form no part of the claimed design. All other surface(s) or portion(s) of the display-coupled financial transaction card not shown in the figures or otherwise described in the specification form no part of the claimed design.
